UNITED STATES PATENT OFFICE

WILLIAM N. OEHM, OF MICHIGAN CITY, INDIANA.

CAR-UNDERFRAME.

1,328,683.

Specification of Letters Patent. Patented Jan. 20, 1920.

Application filed February 21, 1919. Serial No. 278,434.

To all whom it may concern:

Be it known that I, WILLIAM N. OEHM, a citizen of the United States, and resident of Michigan City, county of Laporte, and 5 State of Indiana, have invented certain new and useful Improvements in Car - Underframes, of which the following is a specification, and which are illustrated in the accompanying drawings, forming a part 10 thereof.

The invention relates to car underframes, and the object of the invention is the provision of a frame, the metal composing which is arranged in the most efficient manner for the resistance of stress and to increase its life as affected by corrosion. In general the arrangement of the metal for this purpose consists in an unusual concentration of the metal in the flanges of the 20 structural shapes used, and, in some instances, of the marginal portion of the web.

In the accompanying drawings:

Figure 1 is a side view, partly in section, showing the center sill of a car body and a 25 cross bearer attached thereto;

Fig. 2 is a transverse section on the line 2—2 of Fig. 1;

Fig. 3 is a horizontal section taken on the line 3—3 of Fig. 2, of a cross bearer;

30 Fig. 4 is a vertical section of a cross bearer taken on the line 4—4 of Fig. 2;

Fig. 5 is an end view showing a portion of a bolster and the end of a center sill;

Fig. 6 is a horizontal section taken on the 35 line 6—6 of Fig. 5;

Fig. 7 is a vertical section through the bolster taken on the line 7—7 of Fig. 5, and

Fig. 8 is a vertical transverse section 40 through a center sill showing a modification.

In the drawings 1 indicates the center sill, 2 indicates the cross bearer, 3 indicates the bolster, 4 is used to designate the top cover plate for the center sill, 5 a cross bearer top 45 cover plate and 6 a bottom cross bearer plate, and 7 designates a top cover plate for the bolster. A side sill of the car is shown at 8. 9 designates the web of the cross bearer, while 10 designates the web of the 50 center sill. It will be noted that the center sill, as shown in Fig. 2, has the flanges 11 shown thicker than the web 10 and in this instance the thickness of the flange is carried into the web a distance substantially 55 equal to the width of the flange. To the

back of the lower portion of the web, shown in Fig. 2, an angle member 12 may be riveted to provide increased tensile strength at the bottom of this member. It will also be noted from the showing of Fig. 3, that the 60 end flanges 13 of the cross bearer are thicker than the web thereof and are of substantially the same thickness as the top and bottom flanges 14 and 15 of the cross bearer. The provision of flanges running continuously about each margin of the cross bearer 65 produces a cross bearer which is pan shaped in general configuration.

The top cover plate for the center sills, shown at 4, has its edges, for a width substantially equal to the width of the flange of a center sill, thickened, as shown at 16. The opening in the bolster for the king bolt is shown at 17 and this portion of the frame presents no unusual feature. The thickening of the flanges of each of the channel-shaped members, as well as the margins of the cover plate described, is provided to supply extra strength where the greatest stresses occur and since these regions are 70 the point of attachment of rivets, the construction has the additional function of providing added holding power for the rivets. Moreover, since the greatest corrosion of the frame occurs naturally at these points at 75 the margins of the members, especially at the lower margin thereof, the added thickness of metal at these points will give added life to the car frame since it will, of course, take longer for corrosion to weaken the members. 80 This relative thickness may be attained by making the webs of less thickness than usual thereby giving the usual strength with a smaller amount of metal or it may be provided by making the flanges thicker than 85 90 is the usual practice, thereby using more metal than usual but at the same time producing a frame of greater strength. The modification of the center sill shown at Fig. 8, shows a web which tapers from below upwardly and, as illustrated, has its lower flange thicker than its upper flange. This modification might be applied to each of the other structural members shown, but its illustration in connection with the center 95 sill is believed to be a sufficient disclosure. 100

I claim as my invention:

1. A car frame comprising center sills, bolsters, cross bearers and cover plates, the thickness of the metal of all of said mem- 110

- bers so graduated as to provide increased thickness where greatest stress and greatest corrosion normally occur.
2. A car frame comprising a member 5 channel-shaped in cross-section, the flange of said channel and a portion of the web thereof being thicker than the remaining portion of the web, and an angle member attached to the back of said channel with 10 one flange of the angle in alinement with said flange, the increased thickness of the web giving added strength to said attachment and increased resistance to corrosion.
3. A car frame comprising a member 15 channel-shaped in cross section, a flange of the channel and an adjoining portion of the web thereof being thicker than the remaining portion of the web.
4. A car frame comprising a member 20 channel-shaped in cross-section, the lower
- flange of said channel being thicker than the web and the upper flange thereof and the web being thicker at the bottom than at the top.
5. A car frame comprising longitudinal 25 center sills channel-shaped in cross-section, a cover plate connecting said sills, and cross-bearers projecting from said sills, each of said members being thicker at its margin than at its center portion whereby increased 30 rivet-holding power, increased strain resisting power and increased corrosion resisting power are secured where most needed.
6. A car frame comprising longitudinal center sills channel-shaped in cross-section, 35 a cover plate connecting said sills and attached to the upper flanges of the channels, said cover plate being thicker at its area of attachment than at its middle portion.

WILLIAM N. OEHM.
